Primary Examiner — Darlington Ly(74) *Attorney, Agent, or Firm* — Knobbe Martens Olson & Bear, LLP(57) **CLAIM**

The ornamental design for a personal mobility vehicle, as shown and describe.

DESCRIPTION

Additionally, this application incorporates by reference the entirety of U.S. patent application Ser. No. 29/617,206, filed Sep. 12, 2017.

FIG. 1 is top, front, and left side perspective view of a personal mobility vehicle of our design;

FIG. 2 is a top, rear, and right side perspective view thereof; FIG. 3 is a bottom, front, and right side perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.
